and Lawrence E. Jones and Kenneth E. Wilcox, Los
Angeles, Calif., assignors to Ta-Mar, Inc., Culver City,
Calif., a corporation of California

Application February 14, 1958, Serial No. 49,650

Term of patent 14 years

(Cl. D26—14)

Fig. 1 is a top plan view of a radar antenna, showing our new design; and

Fig. 2 is a side elevational view, the opposite side being substantially a mirror image thereof.

The dominant features of the design reside in the portions shown in the drawing in full lines.

We claim:

The ornamental design for a radar antenna, substantially as shown and described.
